D10-37. OR D 12,775 EX

UNITED STATES PATENT OFFICE.

EUGENE F. MARGOT, OF BOSTON, MASSACHUSETTS.

DESIGN FOR A WATCH-CASE.

SPECIFICATION forming part of Design No. 12,775, dated February 21, 1882.

Application filed January 12, 1882. Term of patent 7 years.

To all whom it may concern:

Be it known that I, EUGENE F. MARGOT, of Boston, in the county of Suffolk and State of Massachusetts, have originated and produced 5 a new and ornamental Design for Watch-Cases or Similar Articles, of which the following is a full, clear, and exact description, reference being had to the accompanying photographic illustration, making part of this specification.

A represents the back and front sides of the case, which may be left plain or ornamented with any figures or design that may be selected.

15 The edge of the case to which my design is adapted consists of the central straight milled bead, which may be of the design shown and now in common use. At each side of this central bead is formed a narrow plain or flat surface, E, and adjoining which is formed the small cable-cord or twist bead B, and adjoining that is formed a narrow plain or flat surface, F, then a narrow or right-angle plain surface, L, and then is formed a pearl bead,

P, then the usual incline or bevels reaching 25 to the back and front of the case, there being two narrow plain or flat surfaces, E, and two cable-cord or twist beads, B, and two very narrow or plain flat depressed surfaces, F, connecting with the right-angle plain surfaces L 30 and the two pearl beads P, all being arranged in the relative positions shown in the photographic illustrations, and the whole forming an original design for the edge of a watch-case.

35

I claim—

The design for a watch-case, consisting of the two narrow plain flat surfaces E E, the two twisted or cable-cord beads B B, the two narrow plain flat surfaces F F, the two right 40 angle plain surfaces L L, and two pearl beads, P P, arranged at each side of the main central bead, as herein shown and described, forming the edge of the case.

EUGENE F. MARGOT.
